Primary Examiner — Barbara Fox*Assistant Examiner* — Aram Kwon(74) *Attorney, Agent, or Firm* — Brinks Gilson & Lione(57) **CLAIM**

The ornamental design for an in-vehicle display device, as shown and described.

DESCRIPTION

FIG. 1 is a perspective view of an in-vehicle display device;
FIG. 2 is a front view thereof;
FIG. 3 is a rear view thereof;
FIG. 4 is a top view thereof;
FIG. 5 is a bottom view thereof;
FIG. 6 is a right side view thereof;
FIG. 7 is a left side view thereof; and,
FIG. 8 is an enlarged view of the enclosed portion 8 in FIG. 1.

The evenly dashed lines are for environmental purposes only and form no part of the claimed design. The dash-dot lines enclosing portions of the claimed design that are illustrated in enlargements form no part of the claimed design.

1 Claim, 8 Drawing Sheets(56)
